UNITED STATES PATENT OFFICE.

JAMES DRAPER BISHOP, OF NEW YORK, N. Y.

BRAIDING-MACHINE.

SPECIFICATION forming part of Letters Patent No. 767,376, dated August 16, 1904.

Application filed September 23, 1903. Serial No. 174,287. (No model.)

To all whom it may concern:

Be it known that I, JAMES DRAPER BISHOP, a subject of the King of Great Britain, residing at New York city, county of New York, 5 and State of New York, have invented certain new and useful Improvements in Braiding-Machines, of which the following is a full, clear, and exact description.

My invention relates to improvements in 10 braiding-machines, and has for its object to produce a simple and effective machine capable of running at high speed and free from many of the objections to which braiding-machines as now constructed are subject, as hereinafter pointed out.

The principal objects to be attained are as 15 great speed of working as is possible and a certain and immediate stopping should one of the yarns or threads which are being braided, 20 come to an end or be broken. High speed is generally obtained by gears connected with mechanism for the purpose of creating an intertwining movement of the bobbins carrying the 25 yarn to be braided, as in the ordinary so-called "waltzing" machine. The stopping mechanism, technically known as the "knock-out," is 30 universally identical in principle and, broadly speaking, consists of threading the yarn through an arm which so long as the yarn remains 35 intact is held out of the reach of a catch, but when the yarn comes to an end or parts is allowed to drop into such a position that it collides with a catch and drives it forward until the driving-gear is disconnected and, in 40 some machines, a brake is applied. To perform these functions with certainty when working at a high speed, the various parts must be made of extra weight, and from this the centrifugal force produced fixes the limit

45 of the working speed.

The knock-out mechanism also requires a number of other parts, which produce complication, and as the contact of these parts when coöperating is violent the life of the machine is thereby proportionately reduced and liability to accident increased. As a complete set 50 of knock-out and other parts must be arranged for each bobbin the machine is constructed to carry and as some machines carry some sixty or more bobbins, the result is a mass of com-

5 plication and multiplication of parts and gearing, all involving much wear and tear and from the friction created requiring very great power to drive.

By my invention the objections mentioned 55 are avoided, the number of working parts is greatly reduced, and the machine rendered more simple and durable, the stopping of the machine being brought about by electricity and the brake being inherent in the machine 60 itself, so as to require no mechanical connection with the bobbins. The working parts can therefore be reduced to a minimum, and the speed attainable is practically limited only 65 by the strength of the yarn employed.

The following is a description of a machine embodying my invention, reference being had to the accompanying drawings, in which—

Figure 1 is a central section of the machine, showing the principal parts. Figs. 1^a and 1^b 70 are detailed views showing the contact-brushes and conductors for establishing electrical contacts between moving parts. Fig. 2 is a plan view of the same. Fig. 3 is a plan view with the upper table or frame partly 75 broken away and the bobbin-carriers and guides being removed. Fig. 4 is a somewhat distorted side elevation of the upper bobbin-carriers for the purpose of explaining the method of operation. Fig. 5 is a plan view 80 of one of the bobbin-carriers. Fig. 6 is a sectional view on the line x x of Fig. 5. Fig. 7 is a view of the bobbin-carrier shown in Fig. 5, partly in longitudinal section and partly in side elevation. Fig. 8 is a view of 85 90 a detail, showing the lower part of the ball-bearing supporting one of the members. Fig. 9 is a diagram of electrical circuits.

Referring more particularly to the drawings, 1 is a standard carrying a vertical tubular bearing or support 2. 3 is a tubular shaft surrounding this tubular bearing 2 and having at its lower end a bevel-gear 3^a and supporting at its upper end a revolving table or frame 4.

95 5 is a disk having a circular groove for the bearing-balls 6, which form a ball-bearing for the shaft 3. The disk 5 is supported by a lever 7, fulcrumed on the point 8 and having upturned projections fitting in recesses 9 of 100

the disk 5. The lever 7 has an upturned end 10, against which bears a pin 11 upon the lever 12, which actuates the clutch member 13 so as to bring it into engagement with the 5 other clutch member, 14, the lever 12 being retracted by the spring 12^a. Upon the outside of the clutch member 13 is a belt 15, by which power is transmitted from some convenient source. To the clutch member 14 is 10 connected the bevel-gear 16, which engages with the bevel-gear 3^a, carried by the hollow shaft 3. The clutch is operated by the lever 12, which is pivotally mounted on the support carrying the journal for the shaft of the 15 clutch member 13. The upper end of this lever 12 is provided with a handle and with bearing-surfaces engaging with rings on the shaft of the clutch member 13 to move that shaft longitudinally. The lower end of the 20 lever 12 is provided with a toothed rack 17, which is engaged by a detent 18, controlled by a lever 19. The end of the lever 19 is adapted to be engaged by a projection 20, mounted upon an armature 21 of the magnet 25 22. The spring 21^a normally retracts the armature 21 when the magnet 22 is deenergized.

Surrounding the tubular shaft 3 is a second tubular shaft 23, having at its lower end a bevel-gear 24, which is also engaged by the 30 bevel-gear 16. The shaft 23 and gear 24 are supported by bearing-balls 24^a, which run in a groove in the supporting-base 24^b. At the upper end of the shaft 23 is a frame or table 25, which carries a set of bobbins 26, carried by 35 spindles 26^a. From these bobbins 26 a thread 27 passes through a guide 72 on the member 73, hereinafter described, then through the guides 28 28^a 29, being delivered by the guide 29 at a point substantially in line with the 40 axis of the bobbin-holder 30, carried by the table or frame 4. This bobbin-holder 30 consists of two metallic end pieces 31 32, which have deep slots 31^a 32^a and are coupled together by a shaft 33, of insulating material, 45 sliding within a tube 34, the shaft 33 having a locking-pin 35 engaging with the slot in said tube 34. A spring 36 in the tubular part 34 bears against the end of the shaft 33. The bobbin 37 fits upon the tubular portion 34 and 50 a bearing portion 38, forming parts of the end pieces 32 and 31, respectively. Above the bobbin-holder 30 is a guide 39 one end of which is pivotally mounted upon a pin 40, screwed into the end piece 31. The other end 55 of the guide 39 is provided with extensions 41, which rest upon the periphery of the end piece 32 and are supported thereby. The two ends of the guide 39 are connected by a block of insulating material 42. The end 39 of the 60 guide has connected to it by conducting-pins 43 the spring contact-piece 44, over which the thread 45 from the bobbin 37 normally passes, thus holding the contact member 44 out of engagement with the second contact member 46, carried by the inner end of the

guide. The end of the guide 39 carrying the extension 41^a is hinged at 41^b and has a spring 41^c acting to keep the extension 41^a in the position shown, its downward movement being limited by a stop 41^d. 70

The bobbin-holders may be described as "floating," being supported upon the table or frame 4 by sprocket-wheels 47 48, and are kept from lateral movement by check sprocket-wheels 49 49 and 50 50. The 75 sprocket-wheels 49 and 50 are mounted on shafts, which are supported by bearings 49^a, secured to the table 4. The bobbin-holders are restrained from upward movement by studs 51 52, having revolving heads 51^a 52^a, 80 which are revolvably mounted by screws 51^b 52^b on said studs 51 52, secured to the frame 4, and bear against inclined flanges 53 upon the heads 31 32 of the bobbin-holders, but do not extend so as to reach to the bottoms of the 85 slots 31^a 32^a and interfere with the threads therein. The sprocket-wheels 48 and 50 are insulated by insulating material 48^a 50^a from the shafts by which they are carried. The stud 52 is secured to the table 4 by the screw 90 54 and insulated therefrom by insulating material 55. The sprocket-wheels 47 and 48 are mounted upon the shaft 56, one end of which carries a bevel-gear 57, which engages with a bevel-gear 58, mounted upon the tubular 95 bearing 2. This gear 58 is connected to the tubular bearing 2 by a spline 59, which acts to hold the gear against rotation and at the same time permits it to have a slight upward and downward movement. The spring 60 100 bearing against the upper part of the hub of the gear 58 tends to keep it in a depressed position. The mandrel 61 or substance to be covered with the braid 62 passes through the opening in the hollow bearing 2, as in the ordinary braiding-machine. 105

The two tables or frames 4 and 25 are provided with frictional contact-surfaces 63 64, which when in engagement act as brakes to stop the mechanism, as hereinafter described. The frame 4 carries a ring of conducting material 65, which is insulated from the frame by insulation 66. This ring is electrically connected with the contact member 46 through the contact-brush 48^b bearing upon the sprocket 110 48, which in turn is in contact with the end piece 32, upon which bear the brush-like extensions 41. The brush 48^b is connected to the ring 65 by an insulated conductor 48^c. Upon the ring 65 bear brushes 67, carried by the frame 25, but insulated therefrom by insulation 67^a. These brushes 67 are electrically connected by an insulated conductor with a conducting-ring 68, carried by the gear 24, but insulated therefrom by insulation 68^a. Upon the conducting-ring 68 bears a brush 69, (supported by an insulating-post,) which is connected to the windings of the magnet 22, which is connected to one terminal of the battery 70, the other terminal being connected by the con- 115 120 125 130

ductor 71 to the base 24^b of the machine. The thread 27 from the bobbins 26, carried by the frame 25, as it leaves the bobbin passes through a guide 72 upon a spring contact member 73, 5 normally holding said contact member out of engagement with the contact 74. The contact members 73 are all electrically connected to the base 24^b of the machine through the shaft 23 and the balls 24^a. The contacts 74 are, however, insulated from the frame by insulating material 74^a. They are, however, electrically connected by an insulated conductor with the ring 68, as shown in the diagram Fig. 9, which, as before explained, is electrically connected 10 through the magnet 22 to terminal of the battery 70 by the conductor leading from the brush 69. A push-button 75 is also arranged so as to engage contact 76 when desired, thus forming a circuit through the magnet 22 and 15 the battery 70 for the purpose hereinafter described, the result being the same as though contact were made between any one of the contact members 44 and 46 or 73 and 74.

The thread from the bobbin 37 passes 20 through the guides 42^a and 41^a directly to the mandrel. The table 4 carries guides 77, which coact with the guides 39 for causing the thread 27 to pass alternately over and under the bobbin-holders 30 and the thread 45 supplied therefrom. 25 Each of these guides 77 has a switch 78, which plays between studs 79 and 80, being held against the former stud by gravity. The guide 39 is so balanced that by gravity and the friction of its supporting-stud 40 it is held in contact with the guide 77, to the left thereof, (see Fig. 4,) always leaving the passage 81 between the right-hand end of the guide 39 and the guide 77 and passage 82 on the other side closed at the point 83 by the engagement of the 30 guides 39 and 77. As the thread passes beneath one of the bobbin-carriers 30—for instance, the middle bobbin-carrier shown in Fig. 4—it is delivered into the passage 81 and passing through the same engaging the switch-arm 78. 35 The switch-arm 78 is lifted by this engagement into the position shown at the right-hand side of Fig. 4, thus bridging over the passage 82 and compelling the thread to pass above the next guide 39. When the thread 40 passes over this guide 39 and comes to the next succeeding passage 82, it finds that the switch-arm 78 corresponding thereto has dropped back into engagement with the stop 79, leaving the passage 82 open, except for 45 the engagement at the point 83, past which the thread can be easily forced.

The operation of the machine is as follows: The threads 45 from the bobbin 37 after having been passed over the contact members 44, 50 around the bobbin 37, and through the openings 42^a and guide 41^a are connected to the mandrel 61. The threads 27 from the bobbin 26 are then passed through the loops 72 on the contact members 73, around the bobbin 26, and 55 through the guides 28 28^a 29 and fastened on

the mandrel 61, each alternate thread 27 being placed on top of one of the guides 39, while the other threads 27 are placed beneath the guides 39 and within the passages 82, as indicated in Fig. 2. The clutch members 13 and 14 are 70 then brought into engagement. This causes the gears 3^a and 24, together with their respective frames 4 and 25, to be revolved in opposite directions. The revolution of the frame 25 should be such as to cause it to move to 75 the left, as indicated by the arrow in Fig. 4. The bobbin-holders 30, by reason of the sprocket-wheels 47 48, mounted on the shafts 56, which are geared to the stationary gear 58, are caused to revolve synchronously in a 80 counter-clockwise direction, as indicated by the arrow thereon in Fig. 4. The threads 27 which are above the guide 39 slip over them, while the threads 27 which are below the guide 39 each pass from a passage 82 into one of the 85 slots 31^a upon the end 31 of the bobbin-holder 30 and into a corresponding slot 32^a at the other end. The revolution of the bobbin-holders carries the threads 27 which are in engagement with the slots 31^a 32^a beneath the 90 bobbins 37 and beneath the threads 45 supplied therefrom. When one of the threads 27 has been carried beneath one of the threads 45, it is delivered into one of the passages 81, along which it passes until it engages the 95 switch-arm 78, which it raises into the position shown at the right-hand side of Fig. 4. It is thus caused to pass above the next succeeding guide 39. The continued revolution of the frames 4 and 25 in opposite directions 100 therefore results in causing the threads 27 to pass alternately over and above each of the threads 45, resulting in the desired braiding.

In case one of the threads 27 breaks or comes to an end the contact 73 is permitted 105 to make engagement with the contact 74, and in case one of the threads 45 breaks or comes to an end the contact 44 is permitted to engage with the contact 46. Whenever this happens, the effect is the same as though the 110 push-button 75 had been operated so as to engage the contact 76—namely, a circuit is established through the magnet 22 and the battery 70, so that the magnet 22 attracts its armature 21. This causes the point 20 to disengage the lever 19, which then moves, so as to disengage the detent 18 from the rack 17. This permits the spring 12^a to retract the lever 12, which separates the clutch members 13 and 14 and simultaneously moves the pin 11 away from the incline 10, permitting the inner end of the lever 7 to fall, together with the plate 5 and the shaft and gear 3 3^a and the parts mounted thereon. The spring 60 causes the gear 58 to follow down along its 115 spline, so as to remain in engagement with the gears 57. The lowering of the shaft 3, together with the frame 4 carried thereby, causes the friction-surfaces 63 to be brought 120 into engagement with the friction-surfaces 64, 130

with the result that a strong braking effect is produced and the two oppositely-revolving frames 4 and 25 are immediately brought to a state of rest. By this simple electrical means, therefore, a very efficient "knockout" is produced, operating whenever one of the threads breaks or comes to an end and operating in such a way as to simultaneously disconnect the machine from the source of power and apply an effectual brake. The push-button 75 is operated whenever the operator desires to stop the machine on any occasion. When the ends of the broken thread are tied together, the outer end of the lever 7 can be depressed and the frame again put into operation. The depressing of the outer end of the lever 7 raises or lifts the frame 4 and separates the circular friction-surfaces 63 64.

In taking out bobbins the ends 31 32 of the bobbin-holder are pressed toward one another against the resistance of the spring 36 until one end is freed from the head 51^a or 52^a. The holder is then removed and the two ends separated, the spring 41^c permitting the guide 41^a to be moved out of the way. The new bobbin is then inserted and the holder replaced in a similar manner.

My invention admits of various embodiments, and I do not wish to be understood as saying that it is limited to the embodiment shown, since various devices, the equivalents of those I have here shown and described, may be substituted without departing from the spirit and scope of my invention.

35 What I claim is—

1. In a braiding-machine, the combination of a series of floating bobbin-holders, bobbins carried thereby, a series of fast bobbin-holders and means for passing the threads from 40 said fast bobbin-holders over and under alternate floating bobbin-holders and means for giving said bobbin-holders a movement of axial rotation.

2. In a braiding-machine, the combination 45 of a revolving frame, floating bobbin-holders mounted thereon, bobbins carried thereby, a second frame revolving in the opposite direction, fast bobbins mounted thereon, and guides for directing the threads from said fast bobbins over and under the alternate floating bobbins, said bobbin-holders having a movement of axial rotation.

3. In a braiding-machine, two frames revolving in opposite directions, and carrying the 55 bobbins containing the yarn to be braided, friction-surfaces on said frames, and means for bringing said friction-surfaces into engagement.

4. In a braiding-machine, two frames revolving in opposite directions, and carrying the bobbins containing the yarn to be braided, friction-surfaces on said frames, a driving means for driving said frames and means for bringing said friction-surfaces into engagement.

5. In a braiding-machine, the combination of a frame, a series of bobbins thereon, a second revolving frame, a series of bobbins, having threads passing from the same, electrical contacts carried by said revolving frame and held out of engagement by said threads, a source of electricity connected to said contacts forming a normally open circuit and means operated by said source upon engagement of 75 said contacts when the thread breaks to stop the relative movement between said frames.

6. In a braiding-machine, the combination of a revolving frame, a series of bobbins carried thereby, a second revolving frame, two 80 sets of electrical contacts held out of engagement by threads from the bobbins on said first revolving frame, a source of electricity having one of its terminals connected to one set of said contacts and its other terminal connected to a conductor on said second revolving frame, forming a normally open electric circuit, means for connecting said conductor to the other set of said contacts on said first frame and means in said electric circuit operating to stop said revolving frames whenever one pair of said contacts comes into engagement.

7. In a braiding-machine, two frames, means for revolving said frames in opposite directions, means for raising and lowering one of said frames, friction-surfaces carried by said frame, brought into engagement when said frame is lowered.

8. In a braiding-machine, the combination 100 of two frames revolving in opposite directions, means for moving one of the said frames longitudinally, friction-surfaces carried by said frames and brought into engagement when said frames are brought together by said longitudinal movement.

9. In a braiding-machine, the combination of a stationary support, a stationary gear-wheel carried thereby, a revolving frame, floating bobbin-holders carried thereby, gears 110 meshing respectively with said bobbin-holders and said stationary gear, and means for passing threads over and under said floating bobbin-holders alternately.

10. In a braiding-machine, the combination 115 of two frames revolving in opposite directions, bobbin-holders carried thereby, bobbins thereon, a shaft for driving said frames, electrical contact devices for each of said bobbin-holders controlled by the threads passing from said 120 bobbins and means for disconnecting said frames from the said driving-shaft upon the engagement of any one of the said contacts with its corresponding contact member.

11. In a braiding-machine, the combination 125 of two frames revolving in opposite directions, bobbins carried thereby, electrical contact devices for each of said bobbins controlled by

the threads passing therefrom and driving means and means for disconnecting said frames from said driving means upon the engagement of any one of the said contacts with its 5 corresponding contact member, and means for simultaneously braking said revolving frames.

12. In a braiding-machine, the combination of two frames provided with friction-surfaces and revolving in opposite directions, bobbins 10 carried thereby, electrical contact devices for each of said bobbins controlled by the threads passing therefrom and driving means and means for disconnecting said frames from the driving means upon the engagement of any 15 one of the said contacts with its corresponding contact member, and means for simultaneously bringing into engagement the friction-surfaces on said revolving frames.

13. In a braiding-machine, the combination of two frames revolving in opposite directions, curved friction-surfaces on each of said frames adapted to be brought into engagement by the longitudinal movement of one of said frames and means for longitudinally moving one of 25 the said frames.

14. In a braiding-machine, the combination of two frames revolving in opposite directions, curved friction-surfaces on each of said frames adapted to be brought into engagement by the 30 lowering of one of said frames, and means for lowering one of the said frames, said means being electrically controlled by contacts controlled by the threads to be braided.

15. In a braiding-machine, the combination of two frames revolving in opposite directions, friction-surfaces on said frames adapted to be brought into engagement, a lever for raising the upper of said frames and means for automatically disengaging said lever upon the 40 breaking of any one of the threads to be braided.

16. In a braiding-machine, the combination of two frames revolving in opposite directions, friction-surfaces on said frames adapted to be brought into engagement, a lever for raising the upper of said frames and means for automatically disengaging said lever upon the 45 breaking of any one of the threads to be braided, driving mechanism and a clutch controlled by said means for simultaneously disconnecting said frames from the said driving 50 mechanism.

17. In a braiding-machine, the combination of two frames revolving in opposite directions, a series of bobbin-holders carried by the upper 55 of said frames, each of said bobbin-holders having two electrically - insulated portions, means for electrically connecting one of the said portions with said frame, means for electrically connecting the other of said portions 60 with a conductor insulated from said frame, a brush carried by the other frame bearing upon said conductor, a source of current and an electromagnetic controlling device, and means for electrically connecting said brush 65 with said source of current and in circuit with said electromagnetic controlling device.

18. In a braiding-machine the combination of two series of bobbin-holders and bobbins movable in opposite directions, the bobbin-holders of one of said series having peripheral slots for receiving the threads from the bobbins of the other series, and means for holding said slotted bobbin-holders in position and causing them to revolve on their axes without 75 interfering with said threads.

19. In a braiding-machine the combination of two series of bobbin-holders and bobbins movable in opposite directions, the bobbin-holders of one of said series having peripheral 80 slots for receiving the threads from the bobbins of the other series, and means for holding said slotted bobbin-holders in position and causing them to revolve on their axes without 85 interfering with said threads and guides for leading said threads to and away from said slots.

20. In a braiding-machine the combination of two series of bobbin-holders and bobbins movable in opposite directions, the bobbin-holders of one of said series having peripheral 90 slots for receiving the threads from the bobbins of the other series, and means for holding said slotted bobbin-holders in position and causing them to revolve on their axes without 95 interfering with said threads, guides for causing each thread to engage the slots of alternate bobbin-holders and pass over the intermediate bobbin-holders.

JAMES DRAPER BISHOP.
